PICKER SPINDLE LUBRICATOR

Oscar V. Payne, Leicester, Mass., assignor to
Crompton & Knowles Loom Works, Worcester,
Mass., a corporation of Massachusetts

Application December 2, 1941, Serial No. 421,384

5 Claims. (Cl. 139—158)

This invention relates to improvements in picker spindle lubrication and it is the general object of the invention to provide mechanism which is operated by motion of the lay to supply the spindle with lubricant.

In certain types of looms the shuttle is propelled by a picker which slides along a rod or spindle secured to the lay and parallel to the shuttle box. In such looms it is desirable to provide adequate lubrication of the spindle to prevent excessive heating thereof by the picker as the latter slides along it. It is an important object of my present invention to provide a portion at least of the picker spindle with a bore which communicates with a tube or the like the receiving end of which extends forwardly and is provided with a guide which directs a pressure lubricator to the inlet mouth of the tube.

The reciprocating lay is in the forward part of its motion when the shuttle is boxed and the picker is in position to start a picking stroke. It is a further object of my present invention to provide the bore of the picker spindle with an outlet which is located between the ends of the picker when the lay is advancing and rely upon the advancing motion of the lay to operate a lubricator. By this arrangement the lay supplies the force necessary to inject oil through the lubricating system at a time when the picker is in position to prevent splashing of the oil.

It is a further object of my present invention to connect the spindle and the lubricating tube by means of a head which is held tightly to the spindle but is capable of angular adjustment relatively thereto.

With these and other objects in view which will appear as the description proceeds, my invention resides in the combination and arrangement of parts hereinafter described and set forth.

In the accompanying drawing, wherein a convenient embodiment of my invention is set forth, Fig. 1 is a plan view of a lay having my invention applied thereto.

Fig. 2 is an end elevation on an enlarged scale looking in the direction of arrow 2, Fig. 1.

Fig. 3 is a detailed vertical section on an enlarged scale on line 3—3, Fig. 2.

Fig. 4 is a detailed horizontal section on an enlarged scale on line 4—4 of Fig. 2, and

Fig. 5 is an enlarged longitudinal section through a portion of the pressure lubricator taken on line 5—5 of Fig. 1.

Referring to the drawing, the lay 10 is driven backwardly and forwardly by means of connectors one of which is indicated at 11. A lay

end 12 projects to the left of the lay and in the present instance is provided with inner and outer box guides 13 and 14, respectively, which receive the tongues 15 of a set of shifting shuttle boxes designated at 16. The boxes are mounted on a rod 17 shown in Fig. 2 and may rise and fall in response to pattern demands.

Each shuttle box is provided with a binder 20 and binder spring 21 to hold the shuttles 8 therein in normally boxed position while the shuttle box is either in inactive non-picking position or when the lay is in the forward part of its stroke. A picker spindle 22 is secured at its inner or right end as viewed in Fig. 1 to the lay end as at 23 and is also secured at its outer or left end to a support 24 carried by the lay end. A picker 25 slides along the spindle and is propelled by a picker stick 26 to move to the right as viewed in Fig. 1, when the lay has reached approximately the mid point of its rearward stroke to propel the shuttle out of the box. When the lay is in forward position the picker will be located as shown in Fig. 1.

In carrying my present invention into effect I provide the left end of spindle 22 with an oil bore 30, see Fig. 3, having an outlet 31 which lies between the ends of the picker when the latter is in the normal position shown in Fig. 1. The bore extends to a head 32 which is held in position by a spring 33 the right end of which as shown in Fig. 2 is fastened to the adjacent part of the lay end by a bolt 34. The spindle has a frusto-conical end 35 which fits into a corresponding pocket 36 in the head 32. A plate 37 secured as at 38 to the lay end has a rearward extension 39 which is threaded to receive the tapered threads of a clamping nut 40 surrounding the spindle. The latter passes through the extension 39 and is held thereto by the nut 40.

The lower end of the head 32 has threaded thereinto a nut 45 which surrounds a thin metal cap 46 the interior of which communicates with a vertical bore 90 in the head. This bore is also in communication with the bore 30 of the spindle so that oil may pass from the interior of the cap into the bore 30.

The lower end of the cap is secured to a flexible oil tight cable 47 which as shown in Fig. 2 may extend downwardly and then forwardly and has the front end thereof provided with a second cap 48 similar to cap 46. Cap 48 extends through a nut 49 which is threaded into coupling 50 the front end of which is threaded as at 51 into the cylindrical rear shank 52 of a

bell 53. The shank 52 is driven into a plate 55 the upper end of which is secured as at 56 to the lay end. Shell 52 is provided with a bore 60 in which is located a light compression spring 61 which urges a ball 62 against the forward restricted end 63 of bore 60. The bell 53 has a conical interior surface which leads to the ball 62.

The tube 47 has a bore 65 the upper end of which is connected to the bore 30 of the spindle as already described and shown in Fig. 3, while the lower forward end of bore 65 is connected by passages through cap 48 and coupling 50 to the cavity 60 which is normally sealed by the ball 62.

In order that lubrication of the spindle may be effected I may use any one of several available pressure lubricators and I do not wish necessarily to be limited to the form shown in Figs. 1 and 2. For purposes of illustration however I have set forth a pressure lubricator including a cylinder 70 into the rear end of which is fitted a cap 71 from which extends a tube 72. The rear end of this tube is provided with a nozzle 73 while the forward end is made with a small cylinder 74 to receive a piston 75 on the end of a rod 76, see Fig. 5. The latter rod is mounted for sliding motion with respect to the cylinder by means of bearing 77 on the front wall 78 of the cylinder and is provided with a hand hold 79. A relatively heavy compression spring 80 is located between the head 79 and the wall 78 to hold the head normally spaced from the cylinder and permit the piston 75 to be located in forward position with respect to the cylinder 74. A ball lock 81 acted upon by a spring 82, both located in the tube 72, prevents return of oil from the rear part of the tube to the cylinder.

As shown in Fig. 5 the piston 75 is loosely mounted on the rear end of rod 76 and has its rear end bent as at 83 to fit against a valve seat 84 on the rod 76. A light compression spring 85 is located between the piston 75 and a nut 86 at the rear end of rod 76. When the hand hold 79 is pushed rearwardly with respect to the cylinder 70 the piston 75 slides along the cylinder 74 to force oil trapped in the latter rearwardly past the ball lock 81, the parts 83 and 84 preventing forward escape of the oil. The hydraulic pressure behind piston 75 is greater than that in front of the piston at the beginning of the rearward motion of the lay and there is a resultant tendency to move the piston forward. The spring 80, however, exerts more force than the combined force of the hydraulic pressure plus spring 85 and therefore rod 76 moves forward faster than piston 75, thereby opening port 81. As the pressure on both sides of the valve seat equalizes the spring 85 will move the piston 75 forwardly until it is seated in the position shown in Fig. 5.

Under normal conditions the lay moves backwardly and forwardly with the funnel or bell 53 advancing with the lay. Such oil as may be in the system carried by the lay is retained by the ball lock 62. When the attendant wishes to lubricate the picker spindle he will hold the pressure lubricator in the position indicated in Fig. 1 and the interior conical surface of the bell 53 will direct the nozzle 73 against the ball 62. The rod head 78 is held firmly in the attendant's hand in such position as to cause engagement of the nozzle with the ball 62 when the lay is in the full line position shown in Fig. 1. As the lay continues to advance the tube 72 and cylinder 70

move forwardly but the attendant prevents forward motion of the head 78, thereby effecting relative rearward motion of the piston 75 in the cylinder 74 to cause oil to move rearwardly through the tube 72 and around the ball lock 81. The oil then passes rearwardly and around the ball lock 62 to enter the chamber 60 and thence moves rearwardly and upwardly as will be apparent from an inspection of Fig. 3 to the outlet 31. This operation occurs while the lay is near the forward end of its motion and while the picker is in such position as to prevent oil from squirming or spattering out of the outlet 31.

From the foregoing it will be seen that I have provided a simple form of picker spindle lubricator including a guide in the form of a bell or funnel to direct the rearward end of a pressure lubricator against a ball lock or the like. As the lay advances the oil from the cylinder 70 is forced rearwardly around the ball lock 62 and upwardly through the bore 65, through the head 32, and into the bore 30. It will also be seen that the flat spring 33 holds head 32 seated against the end of the spindle and presents convenient means for assembling and removing the head 32. Furthermore, the flexible tube 47 leads downwardly from the spindle and all parts of the system extending from head 32 to the conical bell 53 are below bore 30, hence dripping of oil from outlet 31 is prevented.

Having thus described my invention it will be seen that changes and modifications may be made therein by those skilled in the art without departing from the spirit and scope of the invention and I do not wish to be limited to the details herein disclosed, but what I claim is:

1. In a loom picker spindle lubricating system to cooperate with a lubricator having a lubricating end and a cylinder to be held manually, the loom having a picker spindle mounted on a backwardly and forwardly reciprocating lay, the spindle having a lubricant bore therein with a laterally extending outlet, a forwardly facing flared guide on the lay having an outlet at the rear end thereof, and forwardly extending hollow connections on the lay connecting the interior of the spindle bore with the outlet in the guide and having oil therein which moves back and forth with the lay, the lubricator adapted to be held manually in front of the lay as the latter moves forwardly and have said lubricating end thereof directed by the guide to the outlet thereof as the lay advances.

2. In a loom picker spindle lubricating system to cooperate with a lubricator having a lubricant discharging nozzle and a cylinder to be held manually, the loom having a picker spindle mounted on a backwardly and forwardly reciprocating lay and the spindle having a lubricant bore therein with a laterally extending outlet, a funnel shaped guide mounted on the lay having a large end thereof facing forwardly and having a rear small end terminating in an outlet, and forwardly extending hollow connections mounted on the lay to connect the bore in the spindle with the outlet of the guide and having oil therein which moves back and forth with the lay, the lubricator adapted to be guided manually into said funnel and thereafter guided by the latter to said outlet, the forward motion of the lay causing lubricant to pass from the lubricator into said hollow connections.

3. In a loom picker spindle lubricating system to cooperate with a lubricator having a lubricant

discharging nozzle and a cylinder to be held manually, the loom having a picker spindle mounted on a backwardly and forwardly reciprocating lay and the spindle having a lubricant bore therein with a laterally extending outlet, a guide mounted on the lay having a forwardly facing mouth and a rearwardly extending converging surface leading to an outlet in the rear part of the guide, hollow lubricant transmitting means carried by the lay connecting the interior of the bore of the spindle with said outlet, the lubricator adapted to be placed within said opening during advance of the lay to cause engagement of said end with said converging surface, continued forward motion of the lay causing said surface to direct said end to the outlet and cause lubricant to pass into the hollow lubricant transmitting means.

4. In a loom picker spindle lubricating system to cooperate with a manually supported lubricator having a lubricant delivering end, the system being for a loom having a picker spindle mounted on a backwardly and forwardly reciprocating lay, the spindle having a lubricant bore therein with a laterally extending outlet, a guide mounted on the lay having a forwardly facing mouth and a rearwardly extending converging surface leading to an outlet in the rear part of the guide, and hollow lubricant transmitting means carried by the lay connecting the interior of the bore of the spindle with said outlet, the lubricant delivering end of said lubricator to be placed manually within said guide during advance of the lay to cause engagement of said end with said converging surface, continued forward

motion of the lay causing said surface to direct said end to the outlet, said lubricator comprising two parts movable relatively to each other to cause ejection of lubricant from said end into said transmitting means, one of said parts to be moved by the guide and the other to be held manually in position to cause relative movement of said parts due to forward movement of the lay.

5. In a loom picker spindle lubricating system to cooperate with a lubricator having a lubricant discharging nozzle and a cylinder to be held manually, the loom having a picker spindle mounted on a backwardly and forwardly reciprocating lay and the spindle having a lubricant bore therein with a laterally extending outlet, a guide mounted on the lay and movable forwardly therewith and having a rearwardly converging internal surface leading to an outlet in the rear part of said guide, hollow connections between the bore of the spindle and said outlet, a check valve in said connections adjacent to said outlet, said lubricator adapted to have the lubricant delivering end thereof moved manually against said converging surface and thereafter guided by said surface toward said outlet during forward motion of the lay into engagement with said check valve so that the inertia of the lubricator tends to open the valve, forward motion of the lay causing lubricant to pass from the lubricator into said hollow connections as the lubricator is held stationary manually.

OSCAR V. PAYNE.
